UNITED STATES PATENT OFFICE.

CHARLES ROHLFS, OF BUFFALO, NEW YORK.

DESIGN FOR A PORTABLE READING LAMP.

Application filed June 28, 1923. Serial No. 6,606. Term of patent 7 years.

To all whom it may concern:

Be it known that I, CHARLES ROHLFS, a citizen of the United States, residing at Buffalo, in the county of Erie and State of New York, have invented a new, original, and ornamental Design for a Portable Reading Lamp, of which the following is a specification, reference being had to the accompanying drawing, forming a part thereof.

The single figure of the drawing is a perspective view of a portable reading lamp embodying my design.

I claim:

The ornamental design for a portable reading lamp, substantially as shown.

June 26, 1923.

CHARLES ROHLFS.
